METHOD AND APPARATUS FOR BUILDING TIRES

Jorgen I. Haase, Akron, Ohio, assignor, by mesne assignments, to The Goodyear Tire & Rubber Company, a corporation of Ohio

Application November 1, 1951, Serial No. 254,236

39 Claims. (Cl. 154—9)

This invention relates to a method and apparatus for building automobile tires and the like. In building tires on what is known as a crown-type drum the fabric which is first wrapped about the cylindrical surface of the drum to form a sleeve or is pre-formed and then slid in place thereover, must be gathered in at the ends where the fabric extends beyond the ends of the drum and then moved inwardly over the end of the drum and around the bead, since, in the crown type of drum, the bead is located an appreciable amount radially inward of the outer surface of the drum.

It has been the custom in thus gathering the material over the ends of the drum, to pleat the fabric or gather it in and in one way or another wrap the fabric around the bead, which, in the finished tire, restrains the fabric from outward movement, all of which is well understood in the art. These pleats as previously formed were not of uniform size and shape due to the fact that the methods employed were not capable of making them so and there was no means for controlling the formation of the pleats to insure uniformity. In addition, these pleats were then collapsed after forming by a suitable stitching mechanism or by hand before the bead was applied. One big disadvantage of previous known methods of pleating has been that the cords in the fabric are not always properly arranged after the pleating or gathering takes place and, as a result, in the completed tire each of the cords does not take its fair share of the load. Theoretically, each cord should be tensioned the same amount and have the same angular relation with respect to the peripheral edge of the drum as does every other cord and preferably every cord in a layer of fabric should lie within the same plane so that the material will not be too bulky around the bead and the directional load on each cord will be the same, thus giving greater uniformity to the finished tire, not only in appearance but in performance.

The present invention therefore has for its object the provision of a method and a machine for building tires on crown drums whereby the cords of a single layer of fabric lie in substantially the same plane so as to avoid bulkiness of the material in wrapping it about the beads and with the cords all extending inwardly at the same angle with respect to the outer peripheral surface of the drum. Many means have been devised for pleating fabric in order to accomplish by such means what was earlier done by hand but, after the pleats have been formed by such means or the material has been gathered to effect a somewhat uniform distribution of the material at the end of the drum, the material is stitched down in such a manner that the cords lie at various angles and are generally not in the same plane but are overlapping. If they are in the same plane it is a happenstance and not a direct result of using the machine or the process.

Essentially the present method consists in first making a fabric band on a tire drum or pre-forming it and then placing it on a drum with the ends projecting outwardly from the ends of the drum. Then the projecting sleeve-like ends are moved inwardly, while at the same time

2

pleats, scallops, flutes or corrugations are formed, thus forming a sinuous, generally frusto-conical formation having its axis at the axis of the drum and with the ribs extending away from the ends of the drum. The material is not at this stage compacted, stretched or in any way materially distorted, other than to put undulations or scallops of uniform size in the material. The peripheral length of the sinuous portion is substantially that of the peripheral length of the band.

10 The next step is to move a bead or ring against the scalloped portions with a purely axial motion whereby the scallops are flattened in a manner to be brought out more specifically in the specification, and, while these are being flattened, the material is simultaneously moved inwardly toward and finally against the end of the drum which is offset inwardly of the crown. This is all done without putting undue strain on the cords, all in a manner to be described later. During this flattening process the cords, instead of tending to be bunched up and overlapping, are merely squeezed together so that they all lie within the same plane but are crowded together to a higher degree than they were in the original fabric. If, for example, it were intended that the cords be radial when arranged against the end of the drum, every cord would be radial which would mean they would be spaced apart more at the crown of the drum than at the bead area. However this is not generally the case as it is desired that the cords have an angle to the radial direction or the peripheral edge of the drum, as is well understood. 20 The action when cords are non-radial is the same as described above except each cord occupies substantially the same angle with respect to the edge of the drum.

25 During the operation of flattening the scallops, the ends of the material are drawn under the beads and then project in a generally axial direction away from the drum. These portions are subsequently brought up around the outside of the beads and hand-heeled against the carcass and then stitched down against the adjacent portion of the bead and carcass in a well-known manner.

30 If two or more beads are to be applied, then the scalloping ring which is to form the scallops occupies one axial position during the scalloping of one band of fabric for one bead and another axial position for the band of fabric for the other bead.

35 This method is also adaptable to the building of extremely large-size tires. With the large-size tires it is customary to build the tires by the band method, which means that sleeves of multiple plies of fabric are first 40 formed on a separate machine and then slipped over the drum. Some of these sleeves have four to six plies, four being a rather common number. In pleating the ends of such bands by hand there is a considerable amount of material to be handled and it becomes bunched up and 45 very irregular.

50 It has been found, however, that the method that is described herein can be applied to the building of such large tires by first making the bands of a rather small diameter, say as much as a foot less in diameter than the diameter of the drum, then mechanically stretching the band so that it will slip over the drum, whereafter the natural tendency of the band to recover its original diameter causes the protruding ends of the fabric to contract and at least approach the original diameter of the bead, thus causing the material to be drawn down around the rounded edges of the crown, all as will be more specifically pointed out hereinafter. After this step in the process the pleating rings are used as described with reference to machines for building the smaller-size tires.

55 A very important object of this invention is to eliminate the necessity of having to apply cement to hold the fabric against the end faces of the drum or the outer surface

of the drum whereby, after the tire is built, the drum which is made in sections can be readily collapsed and removed from the tire. Previously it has been the custom to provide a cement on the end faces of the drum so that the material which is stitched against the ends of the drum will stay in that position until the bead can be applied. With this invention the bead is acted upon by the stitching mechanism to move the material against the end of the drum and under the bead and, of course, the bead is simultaneously positioned when positioning the fabric. Then, while so positioned, the material is stitched upwardly and over the bead in proper relation thereto so that no cement is required to hold the fabric against the end of the drum. When using cement, as is the customary practice, there is such an adhesion between the material of the tire and the drum that it is generally necessary to use a considerable amount of solvent between the drum and the tire in order to free the drum from the tire before the drum sections can be collapsed and separated from the tire. These drums are normally collapsed axially and then radially and whether this is done by mechanical means or by hand is immaterial because under either condition extreme difficulty is experienced. This method, of course, also eliminates the step of applying a cement to the drum before building the tire and it also prevents the accumulation of cement on the drum, thus eliminating frequent cleaning thereof.

Other objects of the invention will appear hereinafter as the description of the invention proceeds, the novel features, arrangements and combinations being clearly pointed out in the specification and in the claims thereunto appended.

In the drawings:

Fig. 1 is a top plan view partly in section showing in a more or less schematic manner an apparatus for building tires according to this invention;

Fig. 2 is an end view illustrating the manner in which the operator assists the stitching mechanism in the pleating operation;

Fig. 3 is a view similar to Fig. 1 showing the application of the first bead of a tire employing two beads at each end;

Fig. 4 is a section on the line 4—4 of Fig. 3;

Fig. 5 is a view similar to Fig. 3 showing the first bead in place;

Fig. 6 is a cross section taken along the line 6—6 of Fig. 5;

Fig. 7 is a cross section taken along the line 7—7 of Fig. 6;

Fig. 8 is a view similar to Fig. 3 showing the start of the application of the second bead; and

Fig. 9 shows the pleating operation in more detail than it is shown elsewhere and on an enlarged scale. It is shown with reference to the pleating of the second ply;

Fig. 10 shows the first bead in place but on an enlarged scale to more clearly illustrate the functioning of some of the parts;

Fig. 11 is a view taken on line 11—11 of Fig. 10;

Figs. 12 and 13 are end views of the opposite ends of the scalloping ring;

Fig. 14 is a view looking in the direction 14—14 of Fig. 13;

Figs. 15, 16 and 17 are enlarged diagrammatic views illustrating the method of compacting the scallops in the fabric;

Fig. 18 is a front elevational view of a modified tire-building machine partially in section;

Fig. 19 is a view similar to Fig. 18 showing portion of the apparatus on the right side of the machine that could not be included readily in Fig. 18;

Fig. 20 is an enlarged fragmentary view of the means for positioning the scalloping ring at different axial spaces along the shaft;

Fig. 21 shows a modified star wheel for forming pleats when using the apparatus shown in Figs. 18 and 19; and

Figs. 22, 23 and 24 illustrate diagrammatically the manner of utilizing this method for a large-size tire in which the bead diameter is relatively small with respect to the over-all diameter of the drum on which the tire is built.

A conventional crown drum 1 having the end faces or skirts 2 inwardly offset, is shown clearly in Fig. 1. It is against these faces that the sleeve-like ends 3 of the fabric band 4 must be pressed and held in that position so as to conform the fabric to the skirts 2. A shaft 5 rotatably supports the drum in any conventional manner, not shown, and this shaft also supports bead-supporting rings 6 slidably mounted thereon and normally moved to out-of-the-way positions away from the drum until they are ready for use. Also slidably mounted on the shaft 5 is a scallop-forming ring 7 which has an axially extending flange 8 which is scalloped at its free edge as at 9. While not shown in Fig. 1, there is another similar bead-setting ring which is constructed for temporary mounting on the shaft 5 at the left of the drum 1, similar to the mounting shown for this part in the modified form shown in Fig. 19. A stitching-wheel supporting arm 10 mounted in any conventional manner to swing about a fixed axis, or otherwise mounted for movement against the fabric, carries a star wheel 11, better illustrated in Fig. 2, and on the lower side of this wheel and mounted to rotate on the same shaft is a disc 12 which is outwardly flared so that its face at the left, as viewed in Fig. 1, is in a plane perpendicular to the shaft 5 when the star wheel is in operation as shown in Fig. 1. It is to be understood that the wheel 11 and the disc 12, both rotate freely on an axis on the end of the arm 10 and may be integral or formed separately and fastened together later.

As clearly illustrated in Fig. 2 the operator takes hold of the free end of the fabric at one peripheral position, and pulls it tightly down against the outer edge of the scalloped ring 7 which consists of alternate rounded projections and valleys. The star wheel is then pressed against the fabric and forces the material into the open spaces in the scalloped ring. Next, the drum is then rotated by a step-by-step movement accomplished in a manner well understood in the art by a motor which is actuated periodically by a switch controlled by the operator's foot. As the drum rotates, the stitcher wheel forces the material into the grooves in the scalloped ring and it is now only necessary to hold the material lightly in this position after the fabric, which has been pleated by the scalloped wheel, moves past the star wheel or stitcher. This is accomplished by applying a small amount of rubber 13 secured to the ring underneath the projections of the scalloped ring 7 and then applying a small amount of cement to the outer ends of these pieces of rubber prior to the scalloping operation. This cement holds the scallops in place until such a time as the bead 14 supported by the bead ring 6 is moved against the scallops to advance the material toward the end of the drum. It is to be noted that the angle of the material extending down over the crown of the drum to the scalloping ring has substantially the opposite angle to the angle at the end of the drum, namely the skirt 2. This is for a definite purpose. It is to provide just the required amount of material to lie against the end of the drum when the material is moved against the end of the drum, but is short enough to provide enough tensioning of the material to insure a snug fit of that material against surface 2 when it has been moved to the position illustrated in Fig. 5. The length of the scalloped portion of the ring is approximately equal to the peripheral length of the projecting edge of the band.

After the scalloping is completed the bead-carrying ring 6 is slid along the shaft until it is in a position such as illustrated in Fig. 3 with the inner free edge of the drum against the fabric and with the bead 14 against the adjacent portion of the fabric. An ordinary flat-faced

stitcher wheel 15 (Fig. 3) carried on the arm 16 is then used to advance the bead 14 toward the end of the tire while the drum is rotated rapidly and thus flatten out the scallops in the manner which will be described more particularly in connection with Figs. 15, 16 and 17. This advance of the bead, strips the bead from the drum 6 and at the same time moves it into its final position as illustrated in Fig. 5, with the free projecting edges 3 of the fabric projecting in a generally axial direction, after which the ring 6 is moved to an inoperative position. Then, after hand-heeling the free edge of the fabric up around the bead, a stitcher wheel, such as the stitcher 15, may be used to stitch the fabric firmly in place against the carcass in a manner well understood in the art.

In Figs. 15, 16 and 17 the flattening of the scallops is clearly illustrated. One of these scallops is indicated generally by the numeral 17 and the cords of the fabric which are designated by the numeral 18 are embedded in rubber 19. As will be noted from an inspection of Fig. 15, the cords are normally spaced somewhat from each other in the fabric, there being a quantity of rubber between and around the cords. As the stitcher wheel 15 advances in the direction of the arrow during the rotation of the drum, the bead 14 is advanced against the scallop and each individual cord is moved in a generally axial direction so that midway of this operation the middle cords (Fig. 16), which are the first ones contacted, are aligned and moved closer together but not into overlapping relation. This is possible since it should be remembered that the lower free end of the fabric is being turned under the bead by the raised snubbing ring 20 carried thereby and the bead holds the cords with a sufficient tension to prevent circumferential shifting of the cords with respect to each other. Finally when the scalloped portion is completely collapsed the cords will be arranged as illustrated in Fig. 17, with the cords closer together or even in substantial contact with each other. In some cases the crowding of the cords may cause them to become more or less flattened while still maintained in a common plane. The result of this operation is that the cords are all symmetrically arranged and lie in a single plane so that a very smooth wrap is provided around the beads. This eliminates undue bulkiness about the beads in the completed structure and also insures that every cord will be substantially uniformly tensioned.

In the description of Figs. 15, 16 and 17, I have considered that the band is but a single fabric layer with parallel cords. Actually the band is composed of at least two or more layers of cords and the cords in adjacent layers are arranged at opposite angles, generally speaking, so that when the band is stretched, as in the operation of slipping it over the drum, the cords of the different layers change their angle with respect to the circumferential center line of the bands and the angle of the cords in adjacent layers is changed, this angle being decreased in considering the angle formed by the cords with respect to center line of the drum. If and when the cords are crowded together, as described with reference to Figs. 15, 16 and 17, the cords in adjacent layers again change their angle with respect to each other and the angles between the cords change in the opposite sense to that change that takes place when the band is stretched. However, even though both layers are in contact with each other and the cords are embedded in rubber, the cords are permitted to have what is known as a pantographing action due to the fact that the rubber is as yet uncured. However, the action in each layer of cords is as described in connection with 15, 16 and 17, although the cords in adjacent layers extend at opposite angles with respect to each other. These angles are such that when the fabric is positioned along the end of the drum, each of the cords in a given layer occupies a position which, generally speaking, is tangent to the same circle developed about the axis of the shaft and to the circumferential edge of the drum.

The scalloping ring 7 must be mounted on the drum or positioned in relation to the drum, at different axial positions when applying the first bead and the second bead. See Fig. 1 for the position that it occupies in applying the first bead and Fig. 8 for the position that it occupies in applying the second bead. Any means can be provided for accomplishing this result and in the drawings I have shown the ring as being attached to a supporting ring 21, on which are mounted arcuate members 22 which are grooved at 23 and 24 to receive the inwardly projecting edge 25 of the drum. It is to be noted that when the edge 25 is in the groove 24, as in Fig. 1, the ring 7 is in proper position for applying the first band and bead and, if shifted to the groove 23, as in Fig. 8, it is in position for applying the second band along with the bead therefor. In order to provide for assembly and disassembly of the ring and drum and for the shifting of the edge of the drum from the groove 23 to groove 24 or vice versa, the segments 22, as clearly illustrated in Figs. 12, 13 and 14, are each provided with four lugs arranged in pairs, the pairs being designated by the numerals 26 and 27 respectively. When these lugs are aligned with the openings 28 in the flange 25, the scalloped ring may be moved axially with respect to the drum and, after the first pair of lugs 26 has passed through the openings 28, the scalloping ring can be rotated to bring the solid portion of the flange 25 between the lugs 26 and 27, thereby preventing axial movement with respect to the drum and of course if it is desired that the flange be located in the groove 23 the lugs are aligned with the openings 28 and the ring is again moved axially to position the ring in the groove 23 and then rotated to lock the ring against axial movement.

Any suitable means can be employed to hold the scalloping ring in place once it has been located in the proper groove and for this purpose I have illustrated a screw 29 operated by a handle 30 which is threaded through the parts 21 and 22 and adapted to engage the flange 25 or any rigid part of the drum. Usually two of these screws are used, one being for locking the ring in position when it is in the groove 23 and the other when it is in the groove 24. The flange 25 can, if desired, be provided with an opening into which the end of the screw 29 may be projected. The ring, which is to be mounted on the outboard side of the tire drum (that side from which the tire is removed), must be mounted for bodily removal and thus it is desirable to provide a pair of handles 31 by which it may be manipulated and the drum itself may also be provided with a hub 32 connected to the ring itself, as by arms 33, the hub having an opening 34 to be mounted on the shaft 5, thus providing means for centering the ring with respect to the drum.

If, in manufacturing a tire, it has more than one bead the ring is positioned, such as in the position shown in Fig. 8 with the flange 25 in the groove 23. In this position it will be noted that the extending portion 3 of the fabric occupies a smaller angle than in Fig. 1, because now the length of fabric necessary to be brought down against the end of the portion of the carcass previously formed is not as great as is required in bringing the fabric against the surface 2 of the drum in Fig. 1. The operation in applying the second band and the second bead is substantially the same as for applying the first band and the first bead and after this is done the fabric of the second band is hand heeled upwardly over the edge of the tire carcass and then stitched as previously described in connection with Fig. 1.

The carcass is now ready for the application of other elements thereto, such as additional bands, breaker strips, chafing strips and the tire tread, but the application of these additional elements does not form any part of the present invention.

Tire drums of this type are generally made so that they may be collapsed in two directions. First the drum is collapsed axially to diminish its overall length and then

the various sections are collapsed radially inward or removed as individual sections and laid aside, whereby the tire is freed from the drum. In this invention it is proposed to remove the tire drum as a whole from the shaft 5 and the operation of collapsing the drum is accomplished while the tire and the drum are resting on the floor. Due to the fact that in building the tires according to the method described herein no cement is needed to secure the first band to the tire drum, it is possible to perform these collapsing steps very easily, whereas when cement is used it is necessary to first use some solvent in between the bead area of the carcass and the drum to dissolve or loosen the cement holding the carcass to the drum before the drum can be collapsed. All of this requires a considerable amount of time and the use of a certain amount of solvent, thus increasing the cost of manufacture. Also in using cement to hold the first band in place, it is necessary to clean the drum frequently to prevent building up an excess amount of cement on the drum surface.

In Figs. 10 and 11 I have illustrated a detail of the scalloping ring particularly in connection with the snubbing ring 20 thereof. A plurality of springs 35 are arranged peripherally adjacent the snubbing ring 20 and have their free ends extending inwardly toward the tire drum. These assist in centering the bead with respect to the end of the drum and assist in holding the fabric against the bead but not with a positive pressure. This spring is not absolutely necessary but may be found to be desirable in certain instances. Using a spring instead of a rigid portion at this position prevents binding of the bead on the outside of the ring and also makes it easier to move the ring to the position shown in Fig. 8 as the springs 35 can move inwardly underneath the first bead.

In Figs. 18, 19, 20 and 21 I have shown a simplified variation of the machine illustrated in Figs. 1 to 14 inclusive. This machine is substantially the same as that illustrated in the first embodiment but has been simplified for ease of operation and to reduce the time necessary, particularly in setting the scalloping rings in proper position.

In Fig. 18 most of the essential mechanism is shown with the exception of the bead-supporting ring for the outboard side of the drum. This latter is shown in detail in Fig. 19.

In this form of the invention the drum again may be of any desired shape but should be collapsible axially and also radially in any desired manner, or it should be constructed of a plurality of segments which can be readily withdrawn from the tire after the tire has been built. All of this is well understood in the art and no detail of the drum or its mounting is herein shown, not even the drum sections that permit the drum to be dismantled in sections. I have illustrated, however, that the drum, which is designated generally as 36, is made up of two similar parts 37 which are normally spaced apart with the gap between them spanned by a thin metal band 38. The axial collapsing can be accomplished by moving these sections together to close the gap therebetween. The drum is also preferably divided into peripheral sections which may be individually removed from the tire carcass after it is built. It is understood, of course, that the drum will be supported on the shaft in any suitable manner (not shown).

The shaft upon which the drum is mounted to rotate is designated by the numeral 39 and this shaft also carries the scalloping rings 40. These scalloping rings are essentially the same as described with reference to the other form of the invention first described and similar reference characters designate corresponding parts in Figs. 18 to 21 inclusive. However there is one distinction in these scalloping rings and that is, instead of having the rubber fingers such as 13 extend out to the edge of the ring as illustrated in Fig. 1, I provide a ring of rubber 41 which is mounted on the scalloping ring flange 42 at

10 a position such that its outer surface perpendicular to the axis of the shaft 39 lies in a plane substantially adjacent to, but slightly above the bottom of the grooves formed in the scalloping ring, whereby when the fabric 5 is pushed into the grooves, as in Fig. 21, by means of a star wheel 43, the rubber 41 is compressed and, having previously been coated with a quantity of cement, holds the fabric in the bottom of the grooves. This is more desirable in certain respects than the form of the invention shown in Fig. 1 in that the fabric is held under tension in the bottom of the grooves while the bead is moving the fabric through the stages shown in Figs. 15 to 17 inclusive. In Fig. 1 there is no force holding the fabric in the grooves, even though it will normally tend to lie snugly therein. It is also easier with this arrangement to apply a layer of cement as the surface is continuous instead of intermittent and it is only necessary for the operator to take a brush with cement thereon and run it over the rubber strip 41 as the drum rotates in order 15 to get a satisfactory application of the cement. Replacement of this rubber ring is also a simpler operation than replacing the numerous rubber fingers of Fig. 1.

The star wheel 43 shown in Fig. 21 is mounted so that it rotates on an axis perpendicular to the axis of the shaft 25 39 and it has a wider surface than the star wheel in Fig. 1, but in thus mounting the star wheel with its axis perpendicular to the shaft the necessity for a separate ring, such as 12 in Fig. 1, is done away with and the star wheel not only forms the scallops but presses the fabric against the rubber to which the cement has been applied.

In this form of the invention the inboard bead ring 6 and the inboard scalloping ring 40 are permanently mounted on the shaft 39 but the outboard bead supporting ring and scalloping ring are mounted to be removed 30 from the shaft 39 so that upon completion of the tire carcass the drum can be removed and disassembled.

A simple form of locating means is provided for locating the scalloping ring in proper position with respect to the drum instead of using the rather complicated means shown in Figs. 12, 13 and 14. This means is clearly illustrated in Figs. 18 and 20 in which there is a fixed sleeve 44 mounted on the shaft 39 and these each have one or more axial projections 45 adapted to be selectively engaged in the notches 46 (Fig. 18) or the notches 47 (Fig. 20) provided in the hubs 48 of the scalloping ring 7. When the projections 45 are in the notches 46 the scalloping rings occupy positions corresponding to the positions in Fig. 1 when applying the first bead and the first band. When the projections are in the notches 47 50 the scalloping rings are closer to the drum in an axial direction and in this position they are ready for the application of the second bead. If additional bands and beads are required it is easy to see that additional notches of different axial depths can be provided for such a purpose.

The inboard bead supporting ring 6 is mounted on a carrier 49 having a bearing 50 slidably mounted on the shaft 39. The carrier 49 carries hook-shaped lugs 51 engaging over a collar 52 on the hub 48 for the purpose 60 of withdrawing the bead-seating ring from its operative position along with the retraction of the carrier 49. This carrier 49 has an annular grooved ring 53 in which a roller 54 mounted on an arm 55 is adapted to travel. Any suitable means such as an air cylinder (not shown) 65 is provided for actuating the arm 55 to thus move the carrier 49 to the right or left as the case may be, through the intermediary of the roller 54 and the grooved ring 53. Of course the hooked lugs 51 should be separable from the scalloping ring and therefore the flange 52 on the scalloping ring is provided with notches 56 which, when aligned with the hooked ends on the lugs, will permit separation of the scalloping ring and the bead-seating ring.

Turning now to Fig. 19, it may be seen the bead 75 supporting ring is mounted as a separate manually con-

trolled element which can be manually separated from the shaft for the reasons previously described and it is not coupled to the scalloping ring as on the inboard side. This bead-supporting ring 6 is mounted on a carrier designated as 57 which in turn is carried by a shaft 58 and spring-pressed to the left by a spring 59 abutting against a fixed collar 60 on the shaft 58. The shaft 58 is coupled to the shaft 39 by means of a tubular extension 61 having a slot 62 thereon with an offset portion 63 to form with the pin 64 on a bushing 65 on the shaft 39, a bayonet joint which permits easy coupling and separation by the operator. A series of bolts 66 extend inwardly toward the scalloping ring and the ends of these pins limit the movement of the bead-supporting ring to the left under the influence of the spring 59. As the bead is moved from the position shown in Fig. 19 up against the end of the drum, the spring 59 causes the ring 6 to follow the fabric until the stops 66 limit the movement in that direction. After the bead has been applied the scalloping ring is released, disconnecting the shaft 58 from the shaft 39. This is then set to one side until needed for the next bead. The scalloping ring is also removed. The fabric is then turned up around the bead as described in connection with Fig. 1.

In the embodiments of the invention hereinbefore described, wherein the projecting portions of the band are moved into a corrugated substantially conical shape by means of the star wheel and scalloped ring, the conical shape is such that the base or widest portion of the conical shape is nearest the drum. However it is possible to position the scalloping ring inwardly of the edge of the drum so that the conical scalloped portion extends in the opposite direction, bearing in mind that the length of the fabric from the edge of the drum to the conical portion should be a little shorter than is required when the fabric is up against the drum, whereby when the fabric corrugations or pleats are collapsed and the fabric is moved against the end of the drum the material will be under a slight tension. The operation would be substantially the same as in the form of the invention illustrated but the star wheel would be mounted somewhat differently to reach inwardly and under the fabric as it is moved to the inverted conical shape. The slope on the corrugation of the ring would be in the opposite sense and the stops for positioning the scalloped ring on the drum shaft would be also adjusted to position the scalloped ring as desired. However, the preferable form is that illustrated but it is to be understood that the invention is not limited in that respect.

Another feature of the invention that is not illustrated but is readily apparent from an inspection of the drawings is that, instead of using the bead ring to collapse the pleats and move the fabric toward the end of the drum, a separate non-permanent metal ring could be used which would then be withdrawn after it has performed its operation and the bead could then be put in place. This would not ordinarily be desirable as it multiplies the operations necessary but in some instances, as will be more apparent in connection with the description of the invention shown in Figs. 22, 23 and 24, it is highly desirable. In building large tires used in road construction work and the like, many plies are used and these plies are frequently made up initially as bands, each band having four, six or eight plies and then the band thus formed is placed over the drum and the edges of the band are stitched down and around the beads.

For example, if eight plies were used in a band it would be difficult for the operator, first to properly put the corrugations in the fabric and then flatten the fabric corrugations. However the greatest difficulty would be in bringing all eight plies of the band up around the bead in the final turn up and hand heeling operation. Therefore bands of two plies or perhaps four plies can be placed on the drum and the procedure already outlined can be carried on with the exception that a metal ring is used to move

the pleats into collapsed position and against the side of the drum, after which the metal ring is removed and the next two or four plies are operated upon in the same manner after the band has been applied over the first band. The free edges of each band are not now integral but are separate and after removing the metal ring the bead can be put in place and, first, the two or four plies of the last band are first hand heeled up around the bead and then the free edges of the next hand underneath can be hand heeled up around the bead over the second band. This process could be carried out with the bands of two or four or even single plies. For these reasons it can be appreciated that a metal ring can be used in place of the bead for the purposes set forth and the operation of hand heeling and stitching of the eight plies of fabric can be done in stages rather than requiring that all eight plies be handled at once.

In Figs. 22, 23 and 24 there is illustrated diagrammatically the advantages of this process in the manufacture 20 of large-size tires which have large cross-sectional areas and a relatively small bead diameter in comparison to the cross section. In building such tires the stitching of the fabric around the beads is accomplished mainly by hand stitching and pleating of the fabric. The material 25 is bulky and a great amount of time and effort is necessary to hand heel the fabric against the end of the carcass after the bead is in place, the bulkiness of the material is increased by the pleating of the fabric and the result is that the material around the beads is very bulky 30 and the cords do not extend at the desired angles with respect to the body of the carcass. In building tires of this nature bands of four, six and eight plies are used and this increases the difficulty of handling the fabric.

With my process it is possible to reduce the amount of 35 time necessary to fabricate such tires and there is a greater uniformity in the disposition of the cords for the reasons given above in connection with the earlier description. A drum for building such tires is illustrated at 67 and it will be noted that the depth of the skirt portions at 40 the ends of the drum are relatively large and, therefore, to merely place the bands on the outer surface of the drum with just a slight amount of stretching, as with tires such as described in connection with Figs. 1 and 8, would not be sufficient for the reason that there would 45 be too much of the overhanging portion of the sleeve to be gathered in and around the bead without overlapping and the cords could not be crowded together as much as would be necessary for this purpose.

I therefore propose that in making such tires the band 50 be made to a diameter materially less than the outer diameter of the drum, say approximately of a diameter equal to the mean between the diameters of the inner edge 68 of the drum and the outer periphery thereof. In Fig 22 I have illustrated such a band 69 in full lines 55 to show the normal diameter and in dotted lines to show its stretched diameter. This stretching can be done in any one of a number of ways familiar to those working in this art. Such means generally comprises rotatable rollers over which the band is placed and as these rollers 60 rotate the various rollers are moved away from each other to impart a pull on the band to thus stretch it. The diameter of the stretched band is such that the band may be easily slipped over the drum and this should be done shortly after the stretching so that the band does not return to its original shape before application to the drum. 65 In the stretching operation a stress is put in the material due to the pantographing of the cords and the consequent stretching of the rubber and when the stretching forces on the band are released the band tends to return to substantially its original diameter. This being the case after the band is on the drum, the band shrinks in diameter and, while at the center, it is restrained by the drum itself, the edges are unrestrained and therefore they 70 are drawn inwardly until the band is shaped somewhat 75 as shown in Fig 24. The diameters of these projecting

portions are now such that the same may be brought in and scalloped by a scalloping ring similar to those described previously and then stitched around the beads without excessive crowding of the cords. This is for the reason that the spacing of the cords in the projecting portions is substantially the same as in the original band but, since this projecting portion is quite remote from the outer surface of the drum, the cords will not have to be crowded together excessively and will act the same as the cords described in the previous embodiments and particularly with reference to the disclosures in Figs 15, 16 and 17. Thus, a minimum amount of thickness is added to the bead by the wrapping of the plies about the beads. In addition, the cords will all have a more uniform angle as previously described.

Of course additional bands and beads may be applied in a like manner. By using this method the time necessary in building one of these large-size tires is greatly reduced because of the elimination of a great amount of hand operation and by the elimination of cement on the drum. In addition an improved tire results from the use of this process and the beads are less bulky and more uniform.

Fig. 22 illustrates the first step of stretching the band. Fig. 23 illustrates the stretched band immediately after it is slipped over the drum and Fig. 24 illustrates the band after it has had an opportunity to contract at the edges to substantially the initial diameter shown at 69 in Fig. 22.

While certain representative embodiments and details have been shown for the purpose of illustrating the invention, it will be apparent to those skilled in this art that various changes and modifications may be made therein without departing from the spirit or scope of the invention.

Having thus fully described my invention, what I claim and desire to secure by Letters Patent of the United States is:

1. In a tire-building machine in which a tire-building drum is employed for building a tire and the material is initially arranged on the surface of the drum with a sleeve-like portion of said material projecting from at least one end of said drum, the improvement which comprises the combination with said drum of a pleating ring mounted coaxially therewith adjacent said end of said drum and having a sinuous surface thereon against which the projecting part of said sleeve-like portion may be moved into substantial conformity therewith to form pleats in the material.

2. A tire-building machine as set forth in claim 1 in which a stitching wheel is mounted adjacent said drum for moving parts of said sleeve-like portion into substantial conformity with said sinuous surface.

3. A tire-building machine as set forth in claim 1 in which the sinuous surface on said ring is beveled.

4. A tire-building machine as set forth in claim 1 in which the pleating ring is adjustably mounted for positioning it at different axial positions with respect to the end of said drum.

5. A device as set forth in claim 1 in which the pleating ring is provided with a cement-receiving surface in a position to be engaged by the material of said sleeve when moved against said sinuous surface on said ring, whereby to maintain the shape of the portion of the sleeve lying against the ring when said last surface has cement applied thereto.

6. A device as set forth in claim 1 in which said ring has a resilient surface positioned near the sinuous surface to which cement is applied, whereby when the pleats are formed, portions, at least of said material engage the cemented resilient surface and are held in juxtaposition thereby against said sinuous surface of the ring when said projecting part of the sleeve is moved thereagainst.

7. In a tire-building machine in which a tire-building drum is employed for building a tire and the material is initially arranged on the surface of the drum with a

sleeve-like portion of the material projecting from at least one end of said drum, the improvement which comprises the combination with said drum of a pleating ring removably mounted coaxially therewith adjacent said end of said drum having a sinuous surface thereon, against which the projecting portion of said sleeve may be moved in substantial conformity therewith to form pleats in the material, and means for thereafter moving a tire bead against the projecting sleeve portion in engagement with said ring to collapse said pleats and move the material toward the ends of said drum.

8. In a tire-building machine in which a tire-building drum is employed for building a tire and the material is initially arranged on the surface of the drum with a sleeve-like portion of said material projecting from at least one end of said drum, the improvement which comprises the combination with said drum of a pleating ring removably mounted coaxially therewith adjacent said end of said drum of smaller diameter than said drum and having a sinuous surface thereon facing away from the drum and contoured to a length substantially equal to the perimeter of the projecting sleeve-like portion, against which a portion of said sleeve may be moved into substantial conformity therewith to form pleats therein, and thereafter pressing the material thus formed against an end surface of the drum.

9. In a tire-building machine, the combination with a tire-building drum having an outer substantially cylindrical surface and contiguous, inwardly projecting flanges at opposite ends of said drum and of substantial radial depth, of a pleat-forming ring arranged concentrically with said drum with the outer surface thereof of substantially the same diameter as the inner bead diameter of the bead to be used in building the tire, said ring having projections thereon against which projecting portions of a band of material formed on the drum may be moved to pleat the material before moving said material against the adjacent flange.

10. A device as set forth in claim 9 in which a stitcher wheel with projections thereon is mounted for movement into a position adjacent said ring to force the material against the projections on said ring and into the spaces therebetween.

11. A device as set forth in claim 9 in which there is means for advancing a bead against the material engaging said ring, and in which the ring is no larger in external diameter than the internal diameter of the bead, but closely approximates the latter, whereby the bead may be forced over said ring by said advancing means against the adjacent flange on the drum while the ring stitches the material of the band against the bottom of the bead.

12. A tire-building machine including in combination a drum on which tires are to be built, flanges depending from the sides of said drum, a pleating ring mounted coaxially with said drum but having the outer edge thereof spaced axially substantially from one of the said flanges, means for stitching the projecting edge of a tire band on said drum against said outer edge of said ring, and means for moving a tire bead of larger internal diameter than the outer diameter of said ring against the material of said band over said ring against the material between said drum and ring to move said material toward said one of said flanges, whereby the ring stitches the material simultaneously against the underside of said bead as the bead is moved over the ring.

13. The method of building a tire in which the end portions of cylindrical bands are turned inwardly and these ends are then wrapped about beads, that improvement which consists in forming generally radial fluted portions in the material of the inwardly turned end portions of the bands and then substantially simultaneously collapsing all of said fluted portions by a substantially wholly axially directed force.

14. The method set forth in claim 13 in which additional bands are provided and in which additional beads are

similarly applied thereto, which includes the additional step over claim 13 of forming fluted portions in a succeeding band and substantially simultaneously collapsing all of said fluted portions by a substantially wholly axially directed force.

15. The method set forth in claim 13 in which additional bands are provided and in which additional beads are similarly applied thereto, which includes the additional step over claim 13 of forming fluted portions in a succeeding band and substantially simultaneously collapsing all of said fluted portions in a similar manner, but positioning the fluted portion of the succeeding band at a different position axially of the drum prior to collapsing same.

16. The method of building a tire in which the end portions of cylindrical bands are turned inwardly and these ends are then wrapped about beads, that improvement which consists in forming generally radial fluted portions in the material of the inwardly turned end portions of the bands and then moving a tire bead axially of said band against the fluted portions to simultaneously collapse said fluted portions and to stitch the bead thereto.

17. The method of building a tire in which the end portions of cylindrical bands are turned inwardly and these ends are then wrapped about beads, that improvement which consists in forming generally radial fluted portions in the material of the inwardly turned end portions of the bands and then moving a tire bead axially of said band against the fluted portions to simultaneously collapse said fluted portions while at the same time restraining the edges of said end portions close to the inner periphery of the bead to stitch the end portions against the inner circumference of the bead.

18. In a tire-building machine in which a tire-building drum is employed for building a tire and the material is initially arranged on the surface of the drum with a sleeve-like portion of said material projecting from at least one end of said drum, the improvement which comprises the combination with said drum of a snub-ring and pleating ring with the latter having a sinuous surface thereon against which a portion of said sleeve may be pressed into substantial conformity therewith to form pleats in said sleeve, and means for thereafter moving a tire-bead and the pleats over the snub-ring axially against the end of the building drum, thereby causing the portions of the pleats axially opposite to the beads to collapse and the portions radially inward of the bead to be pressed against the bottom of the bead.

19. The method of building a tire in which the end portions of cylindrical bands are turned inwardly and these ends are then wrapped about beads, that improvement which consists in forming generally radial fluted portions of predetermined size and shape in the material of the inwardly turned end portions of the bands in such a manner that the intersection of a cylindrical surface, coaxial with the axis of the tire, with the fluted portions would be a sinuous line continuously advancing circumferentially of the cylindrical surface without regression, and then axially moving a tire bead against said fluted portions to collapse the fluted portions and to stitch the bead thereto.

20. The method of forming tires from bands which comprises the steps of forming the band as a cylinder, turning each of the end portions inwardly toward the axis of the cylinder while maintaining the intermediate portion cylindrical, the end portion being gathered in at spaced peripheral points to form pleats forming collectively a generally frusto-conical shape with the smaller diameter spaced outwardly from the ends of the cylindrical portion of the tire band, moving an annular bead axially against said pleats to simultaneously collapse the pleats into a plane, and moving the bead toward and beyond the outer edges of the cylindrical portion while

70
75

simultaneously stitching the projecting edge of the band against the inner surface of the bead.

21. In the method of building tires on a drum in which a band of fabric, comprising cords and a yieldable material joining the cords, is positioned about the drum with the edges of the band projecting beyond the ends of the drum and in which the edges are then brought down adjacent the end surfaces of the drum and which have a bead applied thereto while in that position, the improvement which comprises the steps of moving at least one of the said edges downwardly over an end surface of the drum while simultaneously shaping the edges to a sinuous shape of substantially the same peripheral length as the peripheral dimension of the fabric, then holding the fabric in that shape and, while so holding the fabric, moving a bead axially thereagainst to move the fabric bodily against the end surface of the drum to thus collapse the adjacent sinuously shaped fabric to flatten same while maintaining an inwardly directed pull on the fabric, whereby the cords of the fabric of one ply are moved closer together in substantially the same plane.

22. The method of building tires which comprises the steps of forming a tire band of a diameter substantially less in diameter than the drum on which the tire is to be built and of a width materially greater than that of the drum, stretching the band substantially to the diameter of the said drum and, while so stretched, encircling the drum with said band, releasing said band so that the ends thereof projecting beyond said drum will return to substantially their unstretched diameter, thereafter shaping the projecting portions to substantially conical shape with the excess material gathered in to form a corrugated surface of predetermined shape, and thereafter moving beads against said ends toward the space enveloped by the stretched portion of the band, to thereby collapse the corrugations.

23. The method set forth in claim 22 in which the edges of the projecting portions of the band are simultaneously stitched against the inner circumferential surface of the beads as the bead is advanced.

24. In the method of building tires on a drum in which a fabric band, substantially wider than the drum, is placed on the drum with at least one edge thereof overhanging an edge of the drum and in which the overhanging edge is turned inwardly toward the axis of the drum and then wrapped about a bead, that improvement in the method of shaping the projecting portions of the band, prior to wrapping it about the bead, which comprises moving the projecting edge against a surface of preformed shape to produce pleats in the fabric, maintaining the projecting edges in intimate contact with said surface to hold the pleats in shape, and subsequently stitching the pleats against the bead.

25. In the method of building tires on a drum in which a fabric band, substantially wider than the drum, is placed on the drum with at least one edge thereof overhanging an edge of the drum and in which the overhanging edge is turned inwardly toward the axis of the drum and then wrapped about a bead, that improvement in the method of shaping the projecting portions of the band, prior to wrapping it about the bead, which comprises moving the projecting edge against a surface of preformed shape to produce pleats in the fabric of predetermined contour, and maintaining the projecting edges in intimate contact with said surface by use of an adhesive between at least portions of said fabric and said surface.

26. In the method of building tires on a drum in which a fabric band, substantially wider than the drum, is placed on the drum with at least one edge thereof overhanging an edge of the drum and in which the overhanging edge is turned inwardly toward the axis of the drum and then wrapped about a bead, that improvement in the method of shaping the projecting portions of the band, prior to wrapping it about the bead, which comprises moving the

projecting edge against a surface of preformed shape to produce pleats in the fabric of predetermined contour, temporarily maintaining the projecting edges in intimate contact with said surface by use of an adhesive between at least portions of said fabric and said surface and then moving a bead toward the adjacent end of said drum and against the pleats in the fabric, radially outward of said surface, to collapse the pleats while at the same time stitching the fabric radially inward of the bead against the inner periphery of the bead.

27. In the method of building tires on a drum in which a fabric band, substantially wider than the drum, is placed on the drum with at least one edge thereof overhanging an edge of the drum and in which the overhanging edge is turned inwardly toward the axis of the drum and then wrapped about a bead, that improvement in the method of shaping the projecting portions of the band, prior to wrapping it about the bead, which comprises moving the projecting edge against a surface of preformed shape to produce pleats in the fabric of predetermined contour, temporarily maintaining the projecting edges in intimate contact with said surface, next moving a bead against the folds to collapse the folds adjacent the inner edge of the bead, and moving the inner edge of the fabric against the inner perimeter of the bead as the bead is advanced toward the end of the drum.

28. In the method of building tires on a tire drum having peripheral and end surfaces upon which the tire material is built to form a tire carcass and in which a band is arranged on the drum with an edge portion thereof projecting beyond the edge of the drum and that edge is then moved downward and inward against the end surfaces of the drum and wrapped about a bead, that improvement which comprises forming uniform pleats in said edge portion projecting from the edge of said drum and positively controlling the shape of said pleats by moving said edge portions inwardly against a pre-formed outwardly facing sinuous surface of the desired shape for said pleats, maintaining said pleats against said surface and collapsing said pleats and wrapping said collapsed pleats about the bead.

29. In the method of building tires on a tire drum having peripheral and end surfaces upon which the tire material is built to form a tire carcass and in which a band is arranged on the drum with an edge portion thereof projecting beyond the edge of the drum and then that edge is moved downward and inward against the end surfaces of the drum and wrapped about a bead, that improvement which comprises forming uniform pleats in said edge portion projecting from the edge of said drum and positively controlling the shape of said pleats adjacent the portion to be wrapped about the beads by moving said edge portions inwardly against a pre-formed outwardly facing sinuous surface of the desired shape for said pleats, maintaining said pleats against said surface and collapsing said pleats and wrapping said collapsed pleats about the bead.

30. The method of building tires that comprises encompassing a building drum with a band of fabric projecting at least from one end thereof, moving the edges of the band downwardly radially inwardly over the adjacent end of the drum, moving a bead against the inwardly ex-

tending edge of said band and continuing the movement of the bead toward the end of the drum while restraining that portion thereof inside the inner bead diameter against axial movement and simultaneously stitching it against the inner perimeter of the bead.

31. The combination with a tire building drum of a pleat-forming device mounted coaxially with the drum near one end thereof, said device comprising an annular member having a plurality of peripherally spaced projections forming an outer serrated surface against which tire fabric, mounted in band form on the drum and projecting from the adjacent end thereof, may be moved to form pleats therein.

32. The combination set forth in claim 31 in which
15 the projections are also bevelled in a direction radially
inward and axially away from the adjacent end of the
drum.

20 33. The combination set forth in claim 31 in which
said device is provided with means for selectively po-
sitioning it at different selected co-axial positions with
respect to the drum.

34. The combination set forth in claim 31 in which the projections and adjacent portions of the annular member intermediate thereof form a sinuous surface progressing peripherally of the annular member in the same direction without retrogression.

35. The combination set forth in claim 34 in which the scalloped edge is bevelled inwardly and axially away from said drum.

30 36. The combination with a tire building drum, of a pleat-forming ring mounted coaxially therewith, comprising an annular member having axially extending projections for use in forming pleats in the tire fabric used in building a tire, said member being provided with
35 a resilient adhesive receiving cushioning member adjacent said projections and arranged radially inward thereof.

37. The combination set forth in claim 36 in which the cushioning material projects axially into close proximity with the outer ends of the projections.

40 38. The combination set forth in claim 36 in which
the cushioning material is arranged axially substantially
inwardly of the outer ends of said projections and is
peripherally arranged so that at least portions thereof
are near the spaces between said projections in a pos-
45 tion to engage tire fabric pressed into the said spaces.

39. The combination with a cylindrical tire building drum of a pleat forming annular member of smaller outer diameter than the drum and mounted co-axially therewith, said device having a rigid sinuous outer surface at one edge thereof progressing peripherally without retrogression, the sinuous surface being of a peripheral length substantially the same as the circumference of adjacent edge of the drum.
